AXLE MOUNTING

Filed July 13, 1946

UNITED STATES PATENT OFFICE

2,630,081

AXLE MOUNTING

Robert C. Kepner, Bloomsburg, Pa., assignor to
American Car and Foundry Company, New
York, N. Y., a corporation of New Jersey

Application July 13, 1946, Serial No. 683,557

2 Claims. (Cl. 105—364)

1

This invention relates to axle mountings in general and in particular to axle mountings for mine or other industrial cars where clearances are small and shocks comparatively great.

In recent years as the loads carried by mine and other industrial cars increased it has been recognized that some type of springing or shock absorbing medium is necessary to prevent destruction of the car body. In the majority of cases, however, it is impossible to use springs of the type customarily used for large railway cars or highway vehicles. Particularly in mine car work tunnel clearances will prevent ordinary types of springing since in order to obtain large capacity the car floors must be lowered as low as possible to get necessary load carrying capacity. It is an object, therefore, of the present invention to provide an axle mounting which will efficiently absorb shocks yet occupy an extremely small space above the car axle.

A further object of the invention is the provision of an axle mounting material interposed between the car body and the axle and capable of permitting limited relative motion between the body and axle in all directions.

A still further object of the invention is the provision of an axle mounting which may be readily applied to existing car structures.

These and other objects of the invention will be apparent to persons skilled in the art from a study of the following description and accompanying drawings, in which

Fig. 1 is a sectional view taken through the car adjacent a supporting axle;

Fig. 2 is a sectional view taken substantially on line 2—2 of Fig. 1;

Fig. 3 is a sectional view taken substantially on line 3—3 of Fig. 1;

Fig. 4 is a sectional view taken substantially on line 4—4 of Fig. 1;

Fig. 5 is a sectional view similar to Fig. 1 but disclosing a modification and taken on line 5—5 of Fig. 6, and;

Fig. 6 is a sectional view taken substantially on line 6—6 of Fig. 5, and Fig. 7 is an enlarged sectional view of the central portion only of Fig. 5.

Referring now to the drawings in detail, it will be seen that the floor 2 of the mine car body is welded or otherwise attached to longitudinally extending sill members 4 having cutouts 6 therein through which the axle A may extend. The sill elements 4 are connected together and braced in Figs. 1 to 4 inclusive by a T-shaped cross sill member 8 having the leg vertically disposed and

the lower flanges 10 horizontally disposed substantially at the level of the upper edge of the opening 6 through the sills. The horizontal flanges 10 of the cross sill have attached thereto a plate 12 to which is bonded or otherwise secured a resilient pad 14. This pad is in turn bonded to a lower plate 16 adapted to rest directly upon the upper surface of the axle A. As clearly shown, particularly in Fig. 2, the plate 12 has its ends coped to permit a projection 18 to extend into the opening 6 formed in the side sills 4. The lower plate 16 is likewise coped to permit its ends to project into the opening and also to permit attachment of thrust members 20 to the axle. These thrust members 20 are spaced slightly from the car side sills and will absorb the side thrusts of the car body and transmit them directly to the axle and thence to the wheel W without any danger of jamming the bearings as would otherwise occur. From the preceding it will be seen that the resilient unit comprising the upper and lower plates 12 and 16 and resilient material 14 may be inserted through the openings in the sill and riveted or otherwise attached to the flanges 10 of the cross sill 8. It is then only necessary for the axle to be inserted through the openings and the thrust plates 20 riveted or otherwise secured to the axle. Due to the coping of lower plate 16 and its engagement with the thrust plates 20, shifting of the plate 16 relative to axle A is prevented. Accordingly, the resilient material 14 will act in shear to cushion slightly the side thrusts prior to engagement of the side sills with the thrust plates 20. The resilient material 14 will also act in shear to control slightly the movements of the axle longitudinally of the body, with total movement restricted by the clearance between the axle and sides of openings 6. Relative vertical motion between the car body and axle will, of course, be absorbed by the resilient material acting in compression and the shock forces will be evenly transmitted through the material and over substantially the entire length of the axle between the wheels.

In the form shown in Figs. 5 and 6 the car floor 30 is suitably attached to side sill elements 32 of bulb angle form and the floor portions are joined by an inverted U-structure 34 extending over and housing the axle. In this instance the resilient unit formed of upper plate 36, lower plate 38 and resilient material 40 is made in two parts for ease of assembly. The two parts, as clearly shown in Fig. 5, are separated by a top member 42 riveted or otherwise secured to the

central portion of the axle housing. Plates 38 as clearly shown are narrower than the space between the side walls of housing 34 and, accordingly, the resilient unit will act in shear to resist both transverse and longitudinal axle movements since the action of the rubber-in-shear is of lower value than the friction between the axle and plate. In order to limit the side motion between the car body and axle and relieve the wheel bearings of improper impact, a side thrust member 44 is riveted or bolted to the center part of the axle and extends downwardly between strap members 46 secured to the axle housing and joining the flanges thereof. As clearly shown in Fig. 5, there is clearance between the thrust member 44 and the strap members 46 which clearance is less than that between the side sills and the wheel bearings. Thus these strap members will not only reinforce the axle housing adjacent its center portion, but will also transmit side thrusts to the U-shaped thrust member 44 attached to the axle as previously described.

It will be seen from the preceding description that the car body is resiliently mounted on the axle for at least slight movement in all directions and it will also be seen that the resilient unit can be readily applied to existing car structures without materially changing the clearances between the car floor and the rail. It will also be seen by persons skilled in the art that various modifications and rearrangements of parts may be made without departing from the scope of the invention as defined by the appended claims.

What is claimed is:

1. In a mine car axle mounting the combination of a substantially square axle, wheels supporting the ends of the axle, an inverted U shaped axle housing covering the entire central portion of the axle and secured to and forming part of the car body, a pair of cushioning units positioned in said axle housing and each comprising an upper plate supporting the axle housing, a lower

10
5

plate supported on the axle, and resilient material bonded to said plates to form the unit and resiliently resist relative movement between the plates, tie means joining the central portions of said axle housing to resist spreading thereof, and U-shaped means secured to the central portion of said axle between the units and having the lower portion thereof engaging said tie means to prevent damaging axial strains from being transmitted to said resilient material and to prevent said body from contacting said wheels.

2. In a mine car axle mounting the combination of an axle, wheels supporting the ends of the axle, a pair of spaced apart cushioning units supporting the mine car body upon the axle and comprising, a pair of spaced apart lower plates supported on the axle, a pair of spaced apart upper plates supporting the car body, resilient material secured to said plates to form the pair of spaced cushioning units, means secured to the body and engageable with the inner ends of said upper plates to hold said units in spaced apart relationship, and means secured to said axle in the space between said units and engaging the car body to prevent damaging axial strains from being transmitted to said resilient material and to prevent said body from contacting said wheels.
